(57) **CLAIM**

The ornamental design for a box with a hexagonal cut-out, as shown and described.

DESCRIPTION

FIG. 1 is a front, top and left perspective view of the box with a hexagonal cut-out showing our new design;

FIG. 2 is a left side elevational view thereof;

FIG. 3 is a right side elevational view thereof;

FIG. 4 is a front elevational view thereof;

FIG. 5 is a back elevational view thereof;

FIG. 6 is a top plan view thereof;

FIG. 7 is a bottom plan view thereof; and,

FIG. 8 is a top plan view of the box with a hexagonal cut-out in an unassembled blank configuration.

The broken lines in the drawings depict optional perforation lines and form no part of the claimed design.

1 Claim, 4 Drawing Sheets(56)
